UNITED STATES PATENT OFFICE

HENRY J. HART, OF HARTFORD, CONNECTICUT, ASSIGNOR TO ROYAL TYPEWRITER COMPANY, INC., OF NEW YORK, N. Y., A CORPORATION OF NEW YORK

TYPEWRITING MACHINE

Application filed November 23, 1928. Serial No. 321,329.

This invention relates to new and useful improvements in typewriting machines generally, although the invention is essentially directed to that type of typewriting machines which includes a vertically shiftable type bar supporting segment.

In the Myers and Handley Patent No. 1,689,888, October 30, 1928, there is disclosed a typewriting machine embodying a vertically shiftable segment, a plurality of type bars pivoted thereon, a plurality of key levers, and connections between each key lever and the associated type bar which includes an intermediate lever and a link connecting the intermediate lever with the type bar. In machines of this type, the platen is supported against vertical movement on the main frame of the machine. The type bars in their normal position of rest are disposed in a substantially horizontal plane with their type heads supported by a head rest fixed to the vertically shiftable segment. Vertically adjustable stops are associated with the segment, such as is disclosed in the co-pending application of George F. Handley, filed October 11, 1927, Serial No. 225,485, for the purpose of limiting the extreme upper and lower positions of the vertically shiftable segment whereby the upper and lower case types on the type bars will cooperate properly with the platen.

It has been found in practice after the stops have been adjusted to center the type with the printing line of the platen, that inaccuracies in manufacture of the platen mounting very often result in the link pivot at the upper end of the intermediate lever not being located in a horizontal plane extending between the upper and lower extreme positions of the pivotal connection between the link and the type bar, and consequently when the segment is shifted, either the type bar will be lifted from its rest position on the head rest, or the key lever will be forced downwardly away from its buffer or stop.

It is, therefore, the principal object of the present invention to avoid the above objections by providing a means whereby the intermediate link may be vertically adjusted, and retained in an adjusted position, so as to

insure the point of connection between the link and the type bar moving equal distances above and below the horizontal line when the segment is shifted to either extreme position.

Another object of the present invention lies in the provision of a bracket for supporting the intermediate links, which bracket is mounted on the key lever support for vertical adjustments relative thereto, the bracket and the support having cooperating parts which insure the bracket being adjusted bodily in a vertical plane whereby the horizontal plane of the bracket, and consequently the horizontal plane containing the pivots of the intermediate links, will be maintained in any position of vertical adjustments.

A further object of the invention lies in the provision of positive means for effecting the vertical adjustment of the bracket relative to its support, and also in the provision of means for securing the bracket against vertical movements in any adjusted position thereof.

In the accompanying drawings:

Figure 1 is a vertical sectional view taken fore and aft of a typewriting machine embodying the subject matter of my invention, and showing the means for shifting the segment,

Figure 2 is a similar view being devoid of the segment shifting means, the view however showing the operating means for the escapement mechanism and ribbon mechanism,

Figure 3 is an enlarged top plan view of the key lever support and showing in section the means for clamping the ends of the bracket thereto,

Figure 4 is a view similar to Figure 3 but showing a modified form of guiding the bracket in its vertical adjustment relative to the support,

Figure 5 is a similar view but showing a further modification, and

Figure 6 is a vertical sectional view showing the modification illustrated in Figure 5.

In the accompanying drawings, I have illustrated only that much of a typewriting machine which is necessary to the full understanding of my invention. My invention is illustrated as being applied to a Royal standard typewriting machine, although it will be

understood that the invention is adapted for use in connection with machines of other types.

- The drawings show a portion of a typewriting machine frame A on which is mounted the usual carriage B having a platen C. The carriage B together with the platen C are supported on the frame A in set position and are not susceptible to vertical adjustment. A segment D is supported on the main frame A of the machine for vertical movements, preferably in the manner and by the shift mechanism shown in the Handley co-pending application Serial No. 225,485 referred to above. A plurality of type bars E are each pivoted on the segment D through the medium of a pivot rod 5 which is mounted on the segment. Each type bar E includes the usual head 6 having upper and lower case characters 7 and 8 respectively, and a heel 9.

The normal or rest position of the type bar E is in a horizontal plane, as shown in Figures 1 and 2, and the head 6 is supported by a head rest 10 which is fixed to and movable with the segment D.

Associated with each type bar E is a key lever F, and these key levers are pivoted at their rear ends upon a horizontally disposed and stationary rod 11 mounted in a support 12 which is in the nature of a bar which extends across the main frame A and is secured thereto. Disposed above the key levers is the usual buffer stop S, and a spring f cooperates with each lever to return the same against the stop.

Each type bar E is operated by the associated key lever F the medium of connections which include an intermediate multiplying lever 13. A link 14 is pivotally connected at its lower end to the key lever F and at its upper end to a front link 15 which is pivoted as at 16 to a cross bar or other support 17 on the main frame of the machine. The front end of the front link 15 is pivotally connected as at 18 to the front end of a long link 19, the rear end of the link 19 being pivotally connected as at 20 to the intermediate lever 13 at a point intermediate the ends thereof. A short link 21 is pivotally connected at its front end as at 22 to the upper end of the intermediate lever 13 and at its rear end as at 23 to the depending heel 9 of the type bar. The intermediate levers 13 are pivoted at their lower ends upon a horizontal rod or shaft 24 which is mounted on a bracket 25 connected to the key lever support 12.

Fixed to the segment D is a stop 26 which is adapted to cooperate with upper and lower vertically adjustable stops 27 and 28 mounted on the main frame A. The segment stop 26 alternately cooperates with the frame stops 27 and 28 to limit the upward and downward movement of the segment. Due to inaccuracies in manufacture the horizontal position of the platen C may become slightly

varied, but by means of the adjustable upper and lower stops 27 and 28, the printing position of the type bar can be adjusted so that the type thereof will be centered relative to the printing line of the platen.

It will be apparent that if, during the downward movement of the segment, the pivotal point 23 moves equidistant from a point above to a point below the horizontal line $\alpha-\alpha$ which contains the pivotal point 22, the type bar E will properly engage the head rest 10 without any material pressure thereon, the key lever F will be permitted to remain against its stop S, and no binding action will occur as a result of the segment D being shifted from one extreme position to the other.

It will be evident, however, that if the point 23 is moved downwardly for a greater distance above the horizontal line $\alpha-\alpha$ than below the same, the link 21 will be in effect moved bodily toward the front of the machine, that is toward the left as viewed in Figure 2. This will result in the type bar E being held at a slight incline so as to hold the head 6 thereof out of contact with the head rest 10. At the same time this forward movement of the link 21 will tend to move the key lever F slightly out of contact with its stop S.

Should, however, the pivotal point 23 be moved downwardly for a greater distance below the horizontal line $\alpha-\alpha$ than above the same, the tendency will be for the link 21 to be moved bodily toward the rear of the machine, that is, toward the right as viewed in Figure 2. This rearward movement of the link 21 will therefore exert a pressure on the type bar E and cause the head 6 to be held with considerable pressure against the head rest 10.

By mounting the bracket 25 for vertical adjustments relative to the key lever support 12, the pivotal point 22 of the intermediate lever 13 may be readily adjusted to suit inaccuracies of manufacture and thereby locate said pivotal point 22 in a horizontal plane midway between the extreme points of travel of the pivotal connection 23 whereby all of the above objections will be overcome. To this end, the intermediate links 13 are mounted on the key lever support 12 for vertical adjustment so as to raise or lower the intermediate levers a distance sufficient to place the point of connection 22 between each link 21 and the associated lever in a horizontal plane midway between the extreme upper and lower points of travel of the pivotal connection 23.

In carrying out my invention, I have provided the bracket 25 which is of inverted U-shaped construction including a cross bar 29 and depending legs 30, 30. The bracket 25 extends transversely of the key levers F and

the cross bar 29 is disposed above the pivoted ends of the key levers. Each leg 30 is formed with a vertical slot 31 and a clamping screw 32 extends through the associated slot and has threaded engagement with the key lever support 12. Thus I have provided a means at each end of the bracket 25 for mounting said bracket on the key lever support for fixed vertical adjustments whereby the point of connection 23 will be moved equidistant above and below a horizontal line by the segment D during either of its shifting movements.

It is also desirable to provide means for guiding the bracket 25 in a vertical direction when being adjusted so as to maintain the pivots 24 of the intermediate links in a horizontal plane in any position of vertical adjustment of the bracket. In Figures 3, 4 and 5, I have respectively illustrated three separate means for guiding the bracket 25 during its vertical adjustment. In Figure 3, the key lever support 12 is provided on its rear face with vertically disposed grooves 33, 33 for receiving the rear faces of the legs 30, 30 of said bracket. The outer faces of the legs 30, 30 are provided with vertically disposed machined faces 34, 34 which have sliding engagement with vertically disposed shoulders 35, 35 formed by the outer walls of the grooves 33, 33. The faces 34, 34 have a tight but sliding fit with the shoulders 35, 35 and consequently when the bracket 25 is adjusted vertically the cross bar 29 of the bracket will be maintained in a horizontal plane.

In the form illustrated in Figure 4, the legs 30, 30 of the bracket 25 are guided vertically relative to the key lever support 12 through the medium of vertically disposed keys 36.

In the form illustrated in Figure 5, the legs 30, 30 of the bracket 25 are each provided with a rearwardly extending seat 37 for receiving a guide pin 38 carried by the key lever support 12. In this form, I have also provided means at each end of the bracket 25 for positively adjusting said bracket vertically in either direction. To this end, the bracket 25, as shown in Figure 6, is provided at each end with a forwardly extending arm 39 which underlies the key lever support 12. An adjusting screw 40 is rotatably supported in the arm 39, and the upper end of this screw has threaded engagement with the support 12. Thus in the form illustrated in Figures 5 and 6, the bracket 25 may be readily adjusted vertically in either direction by first loosening the clamping screws 32, 32 and then turning the adjusting screw 40 in the proper direction. Of course after the proper adjustment has been effected the clamping screws 32, 32 are turned to their clamping positions so as to maintain the bracket 25 against vertical movement in its adjusted position.

In order to provide means for shifting the

segment D, I prefer to employ a mechanism which is disclosed in the Handley application Serial No. 225,485 referred to above, although, of course, other shifting mechanism may be employed if desired.

I have illustrated in Figure 1 of the present drawings, the segment shifting mechanism disclosed in the above mentioned Handley application, and therefore a brief description will be sufficient for an understanding thereof. A key shift lever 41 is mounted on a shaft 42 carried by the main frame of the machine and includes an upstanding arm 43. A bell crank lever 44 is pivoted as at 45 on the arm 43. One arm 46 of the bell crank lever is pivotally connected to one end of a link 47, the other end of said link being pivotally connected to a latch 48 at a point above its fulcrum 49. Also connected to the arm 46 of the bell crank lever 44 is a connection, indicated as a whole at 50, which extends rearwardly and has a loose connection generally indicated at 51 with an arm 52 fixed to a rock shaft 53 mounted on the main frame of the machine. Also fixed on the rock shaft is a forwardly extending rock arm 54 to the forward end of which is pivotally connected an upwardly extending link 55, the upper end of the link being pivotally connected to the segment D. A spring 56 is connected at one end to an arm on the rock shaft 53 and has its other end adapted to be adjustably connected to the main frame of the machine. The spring 56 functions to return the segment D from lower position to upper position. A latch 57 is mounted on the same axis 49 as the latch 48, but extends below said axis to form a depending arm to which is connected one end of a link 58, the other end of the link being pivotally connected to an arm 59 of a shift lock key lever 60. The above description is sufficient to disclose key operated means for shifting the segment D vertically.

The segment D is normally held in its upper position through the medium of the latch 48 engaging the segment stop 26. At this time, the latch 57 is disposed forwardly of the stop 26 as shown in Figure 1. Upon depression of the shift key lever 41, the latch 48 will be first disengaged from the stop 26 and the segment D will be lowered against the tension of the spring 56. Upon release of the shift key 41, the segment will be returned to its upper position by means of the spring 56. Should it be desired to lock the segment in its lower position, the shift lock key 60 is depressed which will cooperate with the shift key 41 and lower the segment against the tension of the spring 56, and after the segment has reached its lower limit, the latch 57 will engage over the segment stop 26 and thereby retain the segment against upward movement until the shift lock key 60 has been released.

I claim:

1. In a typewriting machine, the combination with a vertically shiftable segment, of a key lever, a type bar pivoted on said segment, connections between the key lever and type bar including an intermediate lever, and links respectively connecting the intermediate lever and the key lever and the intermediate lever and the type bar, and means for supporting said intermediate lever for fixed vertical adjustments whereby the point of connection between the last mentioned link and the type bar will be moved equidistant above and below a horizontal line by the segment during its shifting movement.
2. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, a bracket on which said intermediate levers are fulcrumed, and means for mounting said bracket on said key lever support for fixed vertical adjustments whereby the points of connection between the last mentioned links and the type bars will be moved equidistant above and below a horizontal line by the segment during its shifting movement.
3. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, a bracket on which said intermediate levers are fulcrumed, and means for mounting said bracket on said key lever support for fixed vertical adjustments whereby the points of connection between the last mentioned links and the type bars will be moved equidistant above and below a horizontal line by the segment during its shifting movement, said means including cooperating guiding means between the support and bracket for guiding the bracket in a straight line during vertical adjustment.
4. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, an inverted U-shaped bracket extending transversely of and disposed in rear of the key levers and including a cross bar on which the intermediate levers are fulcrumed and depending legs, the cross bar being disposed above the pivot ends of the key levers, and cooperating means between the legs of the bracket and the support for retaining the bracket in a fixed and vertically adjusted position relative to the support whereby the points of connection between the last mentioned links and the type bars will be moved equidistant above and below a horizontal line by the segment during its shifting movement.
5. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, an inverted U-shaped bracket extending transversely of and disposed in rear of the key levers and including a cross bar on which the intermediate levers are fulcrumed and depending legs, said legs being respectively formed with vertically disposed slots, and clamping screws extending through said slots and engaging the support to retain the bracket in a vertically adjusted position whereby the points of connection between the last mentioned links and the type bars will be moved equidistant above and below a horizontal line by the segment during its shifting movement.
6. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, an inverted U-shaped bracket extending transversely of and disposed in rear of the key levers and including a cross bar on which the intermediate levers are fulcrumed and depending legs, the cross bar being disposed above the pivot ends of the key levers, and cooperating means between the legs of the bracket and the support for retaining the bracket in a fixed and vertically adjusted position relative to the support whereby the points of connection between the last mentioned links and the type bars will be moved equidistant above and below a horizontal line by the segment during its shifting movement.

- low a horizontal line by the segment during its shifting movement, said means including cooperating guiding means between the support and bracket for guiding the bracket in a straight line during vertical adjustment.
- 5 7. In a typewriting machine, the combination with a vertically shiftable segment, of a key lever, a type bar pivoted on said segment, connections between the key lever and type bar including an intermediate lever, and links respectively connecting the intermediate lever and the key lever and the intermediate lever and the type bar, means for supporting said intermediate lever for fixed vertical adjustments whereby the point of connection between the last mentioned link and the type bar will be moved equidistant above and below a horizontal line by the segment during its shifting movement, and means for adjusting said supporting means vertically.
- 10 8. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, means for supporting said intermediate levers on said key lever support for fixed vertical adjustments whereby the points of connection between the last mentioned links and the type bars will be moved equidistant above and below a horizontal line by the segment during its shifting movement, and means cooperating with said key lever support for vertically adjusting the support of the intermediate levers.
- 15 9. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, a bracket on which said intermediate levers are fulcrumed, means for mounting said bracket on said key lever support for fixed vertical adjustments whereby the points of connection between the last mentioned links and the type bars will be moved equidistant above and below a horizontal line by the segment during its shifting movement, and means carried by the bracket and cooperating with the key lever support for vertically adjusting said bracket.
- 20 10. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, a bracket on which said intermediate levers are fulcrumed, means for vertically adjusting said bracket whereby the points of connection between the last mentioned links and the type bars will be moved equidistant above and below a horizontal line by the segment during its shifting movement, and means for retaining said bracket against movement in an adjusted position.
- 25 11. In a typewriting machine, the combination with a vertically shiftable segment, of a support disposed in front of and in a plane below the segment, a plurality of key levers fulcrumed on said support, a plurality of type bars pivoted on said segment, connections between the respective key levers and type bars including an intermediate lever, and links respectively connecting the intermediate lever and the key lever and the intermediate lever and the type bar, a bracket on which said intermediate levers are fulcrumed and extending transversely of said key levers, means at each end of the bracket and cooperating with the key lever support for adjusting said bracket whereby the points of connection between the last mentioned links and the type bars will be moved equidistant above and below a horizontal line by the segment during its shifting movement, and means for retaining said bracket against movement in an adjusted position.
- 30 In testimony whereof, I have hereunto subscribed my name.
